UNITED STATES PATENT OFFICE.

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE.

FEEDING MECHANISM FOR SEWING MACHINES.

Application filed July 19, 1926. Serial No. 123,376.

This invention relates to new and useful improvements in feeding mechanisms for sewing machines generally, although the invention is more particularly directed to a top feeding mechanism for blindstitch sewing machines.

The principal object of my invention is to provide a feeding mechanism wherein the feed dog is intermittently given the usual 4-10 motions, that is up and down and back and forth, through the medium of a 3-point cam whereby the feeding stroke of the dog will be made in a substantially horizontal line.

Another object of the invention lies in the provision of a feeding mechanism of the character described which includes an actuating lever having direct contact with the feed dog and with the 3-point cam, and having an adjustable fulcrum for varying the length 20 of the feed stroke of the dog.

Another object of the invention lies in the provision of a top feeding mechanism particularly adaptable for blindstitch sewing machines, and wherein said feeding mechanism is supported by the overhanging arm and directly in rear of the stitch forming mechanism whereby the entirety occupies but very little space.

With these and other objects in view which will more fully appear the nature of the invention will be more clearly understood by following the description, the appended claims, and the several views illustrated in the accompanying drawings, in which

35 Figure 1 is a side elevation of a blindstitch sewing machine equipped with my improved feeding mechanism.

40 Figure 2 is an enlarged front elevation of the stitching head and showing the feeding mechanism associated therewith,

45 Figure 3 is an enlarged end elevation of the sewing head and showing the feeding mechanism,

Figure 4 is an enlarged sectional view 50 taken in the line of feed,

Figure 5 is a horizontal sectional view taken on the line 5—5 of Figure 4, and

55 Figure 6 is a diagrammatic view illustrating the 4-motion path of travel of the feed dog through the medium of the 3-point cam.

60 Figure 7 is a detailed view partly in section showing the mounting of the cam on its shaft.

Like numerals designate corresponding

parts throughout the several figures of the 55 drawings.

In the accompanying drawings, I have shown my invention applied to a "Lewis" blindstitch sewing machine, such as is illustrated in the patent to Mueller 1,539,399, 60 May 26, 1925. This machine comprises a frame including a standard 5, a lower or work arm 6, and an upper overhanging arm 7, the latter being provided at its end with a downward extension 8 which terminates 65 adjacent the outer end of the lower arm 6 and carries a fixed presser foot 9. Above the presser foot 9 is disposed the stitch forming mechanism 10, and below the presser foot 9, and carried by the lower arm 6, is the work 70 supporting plate 11 and plunger 12. The plate 11 and plunger 12 are connected and operated in the usual manner and further description thereof is unnecessary.

A main rotary shaft 13 is journaled in the 75 overhanging arm 7 and carries suitable driving means for actuating the stitch forming mechanism 10, the latter being located in front of and in spaced relation to the depending extension 8 of the frame. Inasmuch 80 as this stitch forming mechanism, as shown in the accompanying drawings, is identical with that shown in the Mueller patent supra, it is deemed to be unnecessary to describe the same in detail.

85 Cooperating with the stitch forming mechanism, to intermittently feed the material, is a feeding mechanism which forms the subject matter of this invention. This feeding mechanism includes a feed dog 14 which is 90 detachably connected to the lower end of an actuating lever 15. This lever is disposed in the space between the downward extension 8 of the frame and the stitch forming mechanism 10. The longitudinal axis of the lever 95 is disposed in a vertical plane and the lever is provided at its upper end with a cam follower 16 for embracing a 3-point cam 17 fixed to the main shaft 13. The cam 17 is provided with three points *a*, *b* and *c* respectively. The lever 15 has a sliding connection 100 with a shiftable fulcrum block 18. The block 18 is provided with a tongue which has sliding engagement in a groove 19 formed in the outer end face of the downward extension 8 105 of the frame. This groove 19 extends upwardly and rearwardly for a purpose herein-after described. The block 18 is formed with

an elongated slot 18^a through which a set screw 18^b projects for engagement with the frame extension 8 and thereby secure the block 18 in any position of adjustment. The 5 block 18 has a forwardly extending integral ear 20 to which is pivotally connected, as at 21, a sleeve 22 which embraces the lever 15. Thus as the cam 17 rotates, the lever 15 will be raised and lowered and also oscillated 10 back and forth in the line of feed.

The high and low points of the cam 17 are concentric and consequently when the feed lever is raised or lowered, the oscillation thereof, while the feed dog is in either of 15 said positions, will result in the feed dog having a substantially straight horizontal movement. This is particularly true by reason of the fact that the fulcrum 21 of the lever is located at a point well removed from 20 the feed dog and consequently the arc described by the feed dog is of such a radius as to be substantially straight and horizontal. It will be also noted that by means of this 3-point cam, the feed motion of the dog 25 is practically a square motion, as indicated by the lines *d*, *e*, *f*, *g*, in Figure 6. The line *f* *g* indicates the substantially straight horizontal "feed" stroke or motion, the line *g* *d* indicates the "up" movement of the dog, the 30 line *d* *e* indicates the "backward" movement of the dog, and the line *e* *f* indicates the "down" movement of the dog. This motion is advantageous in that it permits the dog to be raised vertically from the work instead of 35 having a tendency to draw the work towards the needle.

The stitch forming mechanism 10 includes a sleeve 23 which extends forwardly of the downward extension 8 of the frame and 40 forms a support for the needle lever 24 and also a journal for the thread looper actuating shaft 25. The sleeve 23 is disposed directly above the presser foot 14 and the feed lever 15 is provided with a yoke 26 which 45 straddles said sleeve 23.

From the foregoing it will be observed that the block 18 is shown as being at the upper end of its adjustment and consequently the fulcrum 21 is located at its highest so 50 as to impart the maximum feed travel to the feed dog. It will be observed that if the fulcrum block 18 were moved downwardly in a straight vertical plane, the feed travel would not only be shortened but also the feed 55 movement would be equally divided on opposite sides of a vertical plane containing said fulcrum. Thus under these circumstances the feed dog would begin its feed stroke at points farther and farther in rear 60 of the needle, depending of course upon the adjusted position of the fulcrum 21. This objection is overcome by inclining the groove 19 upwardly and rearwardly. As a result, when the block 18 is lowered it will also be 65 moved forwardly so that the feed stroke will

always begin at the same point relative to the position of the needle. Consequently, I have provided a fulcrum for the lever which is shiftable in two directions, namely, vertically and horizontally, the fulcrum being 70 shiftable in both directions simultaneously.

From the foregoing, it will be seen that I have provided a top feeding mechanism especially adapted for "Lewis" blindstitch sewing machines and have positioned the actuating means for said feed mechanism intermediate the stitch forming mechanism and the depending portion of the overhanging arm, thus forming a very compact mechanism which occupies but very little space. 75

It is of course to be understood that the details of structure and arrangements of parts may be variously changed and modified without departing from the spirit and scope of my invention. 80

I claim:

1. A feeding mechanism for sewing machines comprising in combination, a feed dog, a rotary shaft, a 3-point cam fixed on said shaft, and an actuating connection between the dog and shaft comprising a lever having a sliding fulcrum and connected at its ends directly to said dog and cam respectively for imparting during each rotation of said cam four motions to the dog including a substantially straight horizontal feeding motion, said fulcrum being adjustable longitudinally and transversely of the lever to respectively vary the length of the feed motion of the dog and to maintain the initial point of the feed stroke thereof at a fixed point. 90

2. In a sewing machine, the combination with a work supporting arm and an overhanging arm, of a fixed presser foot fixed to the overhanging arm and disposed adjacent the work supporting arm, a rotary shaft journaled in the overhanging arm, a top feed dog cooperating with the presser foot and work supporting arm, a cam fixed to the main shaft, and a vertically disposed lever fulcrumed on the overhanging arm and having direct connections with the feed dog and cam for imparting intermittent four motion movements to said dog, said lever being fulcrumed on a block adjustably mounted on the overhanging arm for vertical and lateral movements for varying the feed travel of the dog and maintaining the initial starting point of the feed travel at a fixed point. 105

3. A feeding mechanism for sewing machines, comprising in combination a feed dog, a rotary shaft, an actuating lever directly connected to the feed dog and having operative connection with said shaft, and a fulcrum for the lever adjustable longitudinally and transversely of the lever to respectively vary the length of the feed motion of the dog and to maintain the initial 110

point of the feed stroke thereof at a fixed point.

4. A feeding mechanism for sewing machines, comprising in combination a frame, a feed dog, a rotary shaft journaled in the frame, an actuating lever directly connected with the feed dog and having operative connection with said shaft, said frame being provided with a groove inclined to the axis

of the lever, a fulcrum block for the lever 10 adjustable along the groove, and means for securing said block against movement at any predetermined position of adjustment thereof.

In testimony whereof I hereunto affix my 15 signature.

CHARLES W. MUELLER.
